UNITED STATES PATENT OFFICE.

LESLIE W. FLOOD, OF CHICAGO, ILLINOIS.

BRICK-KILN.

1,160,156.

Specification of Letters Patent. Patented Nov. 16, 1915.

Application filed May 18, 1914. Serial No. 839,201.

To all whom it may concern:

Be it known that I, LESLIE W. FLOOD, a citizen of the United States, residing at Chicago, in the county of Cook and State 5 of Illinois, have invented a certain new and useful Improvement in Brick-Kilns, of which the following is a specification.

My invention relates to brick kilns, more particularly to the type known as continuous kilns, and the general object of the invention is to provide a construction such that the heat generated from a given amount of fuel may be utilized to a maximum, thereby giving maximum efficiency and reducing 15 the amount of fuel required.

More specifically, the object of the invention is to so arrange the walls, flues and dampers as to form a series of compartments in the kiln and furnish means for controlling the heated gases in such manner as to cause them to affect a maximum number of bricks; also to so arrange the elements in a kiln of this character that the operation may be continuous. Incidentally, in my 25 kiln the direction of flow of the heated gases is reversed each time the operation is advanced one compartment.

In addition to these objects, it is my purpose to provide a kiln of cheap and simple 30 construction and one that may, if desired, utilize to an unusual degree green bricks in the construction of the kiln itself, thus lowering the cost of maintenance of the kiln and increasing its capacity for a given 35 amount of area and a given amount of fuel.

I accomplish my objects by the construction shown in the accompanying drawings, in which—

Figures 1, 2 and 3 are side, end and plan 40 views, respectively, of a kiln embodying my invention. In these views portions are broken away to better reveal the internal construction. Figs. 4 and 5 are fragmentary views, showing a desirable manner of forming the passages over the top of the dead walls and adjacent portions of the kiln and they form an arrangement of the dampers whereby these passages may be controlled. Fig. 4 shows the passage or opening closed, 50 while in Fig. 5 it is shown to be open. Fig. 6 is a fragmentary vertical section showing the relationship of the passages at the lower portion of the kiln.

Similar numerals refer to similar parts 55 throughout the several views.

In the preferred form, illustrated in the

accompanying drawings, the kiln in its general outline is in the form of a hollow rectangle having a stack or chimney 1, located in the center. While the arrangement of 60 the underground tunnels may be somewhat varied, in the preferred form the gases are led to the stack through a series of tunnels in which 2, 2, represent longitudinal tunnels running beneath the compartments and connected by cross tunnels 3, 3 to headers or stack-tunnels 4, 4 extending longitudinally and discharging into the base of the stack. Dampers 5, 5 are so located as to control the flow from each individual cross tunnel 70 into the headers 4. The floor 6 of the kiln, at frequent intervals, has openings 7, 7, leading down from the body of the kiln into the longitudinal tunnels 2, of which latter there is preferably a plural number, the 75 present design showing four. By preference the openings 7 occur at intervals frequent enough so that there shall be four of them leading into each longitudinal tunnel from each compartment of the kiln. According 80 to the present design, therefore, there are sixteen down passages from each compartment of the kiln to the tunnels beneath. Said down passages are controlled by dampers which consist preferably of refractory 85 slabs 8. These may be loosely laid over the mouth of the passage and controlled by hooks or pokers inserted through the arches 9 in the manner familiar to those skilled in the art. 90

In the best design, the permanent walls of the kiln comprise the outer longitudinal walls 10, the inner longitudinal walls 11 and the end walls 12. The inner court or area 14 is accessible through one or two doors or 95 openings 15. Access to the compartments themselves is had through doors or openings 16, while access to the arches is had through smaller doors or openings 17.

One of the most important characteristics 100 of my kiln is the internal arrangement and the formation of the flues and passages; and these will now be described.

In setting the bricks in the kiln arches 20 are formed in the well-known manner, these 105 arches being arranged opposite to the openings 17 and above the passages 7, 7 which lead down through the floor to the tunnels beneath. At proper intervals, for example fourteen feet more or less, I form substantially imperforate walls 21. These constitute what may be termed dead walls and 110

divide the kiln into a number of compartments, the present design of kiln showing 8 compartments on each side. These dead walls may be formed of green bricks or 5 burned bricks, although ordinarily green bricks are preferred for they will become burned during the process and hence result in increasing the output. Above the arches the bricks are set in the usual way with interstices between them so that the hot gases 10 may flow through the pile. When the bricks have been set to a sufficient height, for example, to a point slightly beneath the top of the outer walls 10, 12, as shown in Figs. 15 and 2, a horizontal duct or passage 22 is formed; and while the manner of forming it may be varied somewhat, I prefer to place brick 23 on end on the top of the pile, thus forming a sort of colonnade for supporting 20 slabs 24 of refractory material which form a substantially air tight roof. A single brick may readily support the adjacent corners of four different slabs, as indicated. The dead walls 21 are terminated practically 25 flush with the top of the pile of bricks, and hence, in the absence of dampers, there is in the preferred construction a duct or passage at or near the roof of the kiln extending completely from one end of the kiln 30 to the other. In fact, the passages on the two sides of the center court, are connected by a passage 25 best shown in Fig. 2, said passage 35 being formed preferably in the same manner as the passages 22, to-wit: by placing refractory slabs 24 upon bricks 23 placed on end under the corners of the slab. Said bricks 23 rest upon a floor 26 of refractory material resting upon a platform supported 40 upon metallic beams 27 or other suitable supports.

The horizontal flow over the top of each dead wall is controlled by valves or dampers which may well be formed of slabs 28 of refractory material. The arrangement 45 is best shown in Figs. 4 and 5, where it will be apparent that over the top of each dead wall, in line therewith, the slabs 24 are spaced apart to form a passage 29, wide enough to receive a slab 28 when placed on 50 edge. When it is desired to close the passage over the top of a dead wall, said slabs 28 are inserted into the passage 29 as shown in Fig. 4. This cuts off communication from one compartment to the next. When it 55 is desired to open up the passage to permit the gas to flow from one compartment to the next, the slabs 28 are withdrawn, and the space 29 closed at the top by laying the slabs 28 over it in the manner shown in Fig. 5. 60 This makes a simple and efficient dampering means. The same means may be employed in the passage 25 shown in Fig. 2. By employing, as I prefer, a number of slabs end to end in each opening 29, it is 65 possible to vary the available area through

which the gas may flow; for if desired, some of the slabs may be placed vertically and others in the same row at the same time horizontally.

From the foregoing it will be evident that 70 when the dead walls are in place, the kiln is divided into a number of compartments which for convenience I have indicated in Fig. 1 as A, B, C, D, E, F, G, H. A similar series will, of course, exist at the far side of 75 the kiln represented by the portion at the left of the stack in Fig. 2 and above the stack in Fig. 3.

In operation, let it be assumed that the 80 bricks in compartment A have recently been burned and are still in process of cooling; also that compartments B, C, D and E are filled, the succeeding compartments being filled or in the process of being filled. All of the dampers 5, except one, are closed. 85 Let it be assumed that the damper leading from the compartment E is open. A fire will now be placed in the arches at the bottom of compartment B and the dampers 28 will be so arranged that the passages 90 over the top of the dead walls between A and B and between B and C and between D and E are open, while the passages between compartments C and D and between compartments E and F are closed, as illustrated 95 in Fig. 1 of the drawings. The dampers 8 controlling the passages 7 are closed in the bottom of compartments A and B and are open in the bottom of compartments C, D and E. The result is that the gases flow up 100 through compartment B over the top of the dead wall and down into and through compartment C and thence through the longitudinal tunnels 2 to the transverse tunnel 3 under compartment E, thence into the tunnel 105 4 and out through the stack. At the same time, the hot gases arising from the cooling bricks in compartment A will pass up through compartment A over into the top of compartment B and thence through the 110 horizontal passage at the top of compartment B where they will mingle with the gases in compartment B and pass with them over into and down through compartment C. As a result, the heat will be great 115 enough in compartment B to burn the bricks therein and to heat to quite a high temperature the bricks in compartment C.

In consequence of this construction, and 120 method of operation it is obvious that the heat of the fuel is utilized efficiently. Compartment C, although it has no fire under it, receives heat from both compartment A and compartment B and hence bricks in compartment C are well heated before the fire 125 is placed under them. Compartments D and E also receive a certain amount of heat as they are open to the longitudinal tunnels 2.

When the bricks in compartment B are 130

completely burned, the process will be advanced one step—that is, a fire will be made in the arches under compartment C and the respective dampers of each succeeding compartment will be positioned in the manner in which the dampers of the preceding compartments were positioned during the preceding step or stage. The flow will then be up through compartment C and down through compartment D. With a kiln constructed in the manner shown, this process may be repeated without interruption and the kiln will therefore be continuous in its operation.

15 Although the method of operation above described, in which the gases of combustion arising from the bottom of the compartment being fired are led up through that compartment and down through the next succeeding compartment and thence through tunnels under the next two succeeding compartments before being led into the stack, there is nothing to prevent a kiln of my construction being operated in such manner 25 that the gases of combustion will be permitted to finally escape from the compartment next succeeding the one in which burning is taking place; for example, when compartment B is being fired the gases might 30 be shut off from compartments D and E and permitted to escape through the stack from the bottom of compartment C and the transverse tunnel 3 beneath said compartment C.

35 As a result of my construction it is possible to operate the kiln continuously right around the stack, the end compartment in one row being suitably connected to the end compartment in the row on the other side 40 of the stack.

It will be observed that as a result of my construction in which the different compartments are separated by substantially imperforate dead walls, with passages at 45 the top of the walls leading from one compartment to the other, and passages at the bottom of the compartment leading from one compartment to the other, it is possible to so operate the kiln that the compartments 50 themselves become flues or ducts, communicating with each other for the continuous passage of the gases.

Having thus described my invention, what I claim as new, and desire to secure by Letters Patent, is:

55 1. A brick kiln having a stack, a plurality of compartments controllably communicating with each other at the top, a separate passage leading from the bottom of each compartment to the stack, a passage leading from the bottom of one compartment to the bottom of the adjoining compartment, and means for independently controlling each of said passages whereby the operator is afforded a choice in connection with each com-

partment as to whether the gases shall flow from the bottom of that compartment to the bottom of the adjoining compartment or directly to the stack.

2. A brick kiln having dead walls forming at least four compartments, each of said compartments communicating with the one adjacent thereto at the top, dampers at the top of each dead wall for controlling the passage of gases from one compartment to the next, a stack, a passage for each of said compartments leading from the bottom thereof, each of said passages being provided with a damper and each of said passages communicating with said stack, said compartments communicating with each other at the bottom, and means for controlling the flow from the bottom of one compartment to the bottom of the two compartments adjacent thereto.

3. A kiln having dead walls forming at least four compartments, there being an opening at the top of each dead wall whereby gases may pass from one compartment to the other, dampers for each of said openings, a stack, a passage leading from the bottom of each compartment to said stack, a damper in each of said passages, a tunnel beneath the dead walls communicating with the bottom of all of said compartments, and means for independently controlling the flow from the bottom of each compartment to said tunnel.

4. A brick kiln having dead walls forming at least four compartments, a duct at the top of each dead wall, means for independently controlling said ducts, a tunnel communicating with the bottom of each of said compartments, means for independently controlling the flow between said tunnel and each of said compartments, a stack, and means individual to each of said compartments for independently controlling the flow of gases from said tunnel to said stack.

5. A brick kiln having dead walls forming compartments, a cover over the kiln, ducts at the top and at the bottom of each compartment affording communication with the compartments on either side, dampers for independently controlling the flow through said ducts, a stack, and a duct leading from each of said compartments to said stack.

6. A brick kiln having dead walls forming compartments, a cover over said kiln a slight distance above the top of the dead walls whereby passages are formed between the cover and the top of the walls, said cover having slots above and extending in line with each wall, and slabs of refractory material of a thickness slightly less than the width of said slots and a length greater than the width of the slots, whereby the slabs may be inserted into the slots and rest upon the dead walls to arrest the flow of gas, or

may be laid horizontally to form covers for closing said slots, ducts at the bottom of said compartments forming passages from each compartment to the ones adjacent thereto, means for controlling the flow of gas through said ducts and means for leading the gas from said ducts to the atmosphere.

7. A brick kiln comprising two parallel inclosures each provided with longitudinal walls and end walls, dead walls within each inclosure dividing the same into a plurality of compartments, a longitudinal tunnel beneath each inclosure communicating with the different compartments, a stack, stack tunnels connecting said longitudinal tunnels with said stack, a cover at the top of the kiln, a duct beneath said cover connecting each compartment with the compartment on either side thereof and connecting the end compartment of one inclosure with the adjacent end compartment of the other inclosure, and means for controlling the gas flow through said ducts and tunnels.
8. A brick kiln comprising a stack, two parallel inclosures each provided with longitudinal walls and end walls, dead walls within each inclosure dividing the same into a plurality of compartments, a longitudinal tunnel beneath each inclosure communicating with said stack, a stack tunnel extending parallel to the longitudinal tunnels and constituting a header, a branch tunnel leading

from the longitudinal tunnel beneath each compartment to the header tunnel, dampers 35 controlling each branch tunnel, a cover at the top of the kiln, a duct beneath said cover connecting each compartment with the ones adjacent thereto, means for controlling the gas flow from each compartment into the 40 longitudinal tunnel beneath, and means for controlling the gas flow in the duct at the top of each compartment.

9. A continuous kiln having a floor, a plurality of dead walls rising from said floor and dividing the kiln into compartments, longitudinal tunnels beneath the floor, said tunnels having openings leading therefrom to the bottom of each compartment, means for independently controlling said openings 45 and at the same time leaving said tunnels unobstructed, a transverse tunnel leading from the bottom of each of said compartments to the atmosphere, a damper for each of said transverse tunnels, a cover over said kiln, ducts beneath the cover leading from each compartment to the next, and means for independently controlling said ducts.

In witness whereof, I have hereunto subscribed my name in the presence of two witnesses.

LESLIE W. FLOOD.
